STORM WINDOW CONSTRUCTION

Filed Oct. 24, 1945

UNITED STATES PATENT OFFICE

2,427,915

STORM WINDOW CONSTRUCTION

Walter M. Krantz, Youngstown, Ohio, assignor
to Ace Storm Window Company, Youngstown,
Ohio, a corporation of Ohio

Application October 24, 1945, Serial No. 624,165

4 Claims. (Cl. 160—91)

1

This invention relates to a storm window construction and more particularly to the formation of combination, interchangeable sash units employed therein.

The principal object of the invention is the provision of a storm window construction incorporating sash units having means formed thereon facilitating their storage adjacent the storm window.

A further object of the invention is the provision of a storm window construction including interchangeable screen and glazed sash units.

A still further object of the invention is the provision of a storm window construction including a master frame having interlocking sash carrying members for the reception of interchangeable glazed and screened units and including means facilitating the storage of either the glazed or the screened sash.

The storm window construction illustrated and described herein has been devised to form a simple and efficient means of providing for at-hand storage of interchangeable glazed or screened sash units as employed with storm window constructions of the combination type. It is known in the art that several storm window constructions have been devised which provide a master frame capable of being mounted on a window opening as, for example, on a dwelling house, and which master frame is adapted to receive in operative relation therein one or more removable glazed or screened sash inserts so that the master frame may be employed for the positioning of the glazed inserts in forming a weather-tight storm window and also be employed for receiving a screened sash insert depending on the season of the year. In the past it has been common to provide this type of storm window with one glazed upper sash which is usually left in the master frame throughout the year, and to provide one glazed lower sash for use in the master frame during the winter and one interchangeable screened sash for use in place of the lower glazed sash in the summer. The present invention relates to the formation of the sash and particularly the normal lower glazed sash and the interchangeable screened sash in a manner so that each serves as a means for retaining the other in elevated relation and thereby provides a simple and efficient means of storage.

With the foregoing and other objects in view which will appear as the description proceeds, the invention resides in the combination and arrangement of parts and in the details of con-

2

struction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a vertical side cross sectional view with parts broken away illustrating a combination storm window construction and interchangeable glazed and screened sash.

Figure 2 is a vertical cross section with parts broken away illustrating a combination storm window construction and interchangeable glazed and screened sash taken substantially on line 2—2 on Figure 3.

Figure 3 is a partial front elevational view of the storm window construction illustrated in Figures 1 and 2.

Figure 4 is a cross sectional detail of the sash framing member illustrated in Figures 1 and 2, taken substantially on line 4—4 of Figure 5.

Figure 5 is a partial elevational view of the sash framing member illustrated in Figure 4.

By referring to the drawings and Figures 1, 2 and 3 in particular, it will be seen that a storm window has been disclosed which consists of a master frame 10 adapted for installation on the exterior of a window opening. The master frame 10 includes a plurality of sash receiving members 11 which form is disclosed in my copending patent application on Storm Sash, Serial No. 609,455, filed August 7, 1945. These sash receiving members 11 form channels 12 and 13 for the reception of lower and upper sash 14 and 15, respectively, the lower sash 14 (in Figure 1) being provided with screening material and being interchangeable with a third sash 14A provided with glazing material. The third sash 14A which is interchangeable with the sash 14 is illustrated in Figure 1 in elevated, stored position and is shown resting on the uppermost section of the sash 14 by means of engaging T-headed sections 16 and 16A, respectively, formed horizontally on the upper and lowermost sections of each of the sash 14 and 14A.

In Figure 2 of the drawings the sash 14 and 14A are shown in reversed position, the glazed sash 14A being shown in position in the lower portion of the storm window construction where in conjunction with the upper glazed sash 15 it forms an efficient weather-tight storm window. In Figure 2 the screened sash 14 is shown in stored position, the engaging T-headed sections 16 and

16A serving to hold it in the position shown in exactly the same manner as the glazed sash 14A is held in elevated position on the screened sash 14 in Figure 1. The extra sash when in the above mentioned stored position may be leaned at its upper end against the adjacent window frame and may be retained there, if desired, by a suitably located hook or turnbutton, not shown.

It will thus be seen that by providing a storm window construction incorporating a pair of glazed sash 14A and 15 that an efficient storm window may be formed for winter use and that the formation of the sash framing members employed in forming the sash 14 and 14A enable the extra screened sash 14 to be stored during the winter immediately inside the upper sash 15 and that during the summer time the positions of the sash 14 and 14A may be reversed and the glazed sash 14A stored in the window construction itself. The T-headed sections 16 and 16A are illustrated in greater detail in Figures 4 and 5 of the drawings wherein cross sectional and plan elevations are given, it being observed that the section 16 includes an inner channel 17 for the reception of the glazing unit or the screening unit and an outer channel 18 which registers with the channel 12 in the sash receiving members 11. The T-headed sections 16 are formed on two of the sections of cut and mitered material used in forming the sash frames, the lower horizontal section and the upper horizontal section thereby providing the means enabling the extra sash, either screened or glazed, to be stored in the storm window construction.

In Figure 3 of the drawings a plan view of the interior of the storm window construction is illustrated and indicates the attractive appearance of the glazed sash 14A and screened sash 14, the screened sash 14 being stored in elevated position, it being observed that the T-headed sections 16 form a convenient handle member facilitating the handling of the interchangeable screened and glazed sash 14 and 14A, respectively.

It will thus be seen that by providing a storm window construction formed in accordance with this disclosure and including the T-headed sections 16 and 16A formed horizontally on portions of the framing members employed in forming the sash 14 and 14A, respectively, the sash may be interchangeable and stored in the window construction simply and efficiently and the T-headed sections form handles convenient to the operator of the storm window as well. The construction disclosed eliminates the necessity of removing the

glazed or screened lower sash 14 or 14A and storing it elsewhere in the premises. It thereby contributes to a more desirable storm window construction than has heretofore been known in the art.

Having thus described my invention, what I claim is:

1. A storm window assembly comprising in combination a master frame having a plurality of sash guides registrable therewith forming sash receiving channels, a pair of glazed sash removably positioned in said channels and an extra interchangeable screened sash for alternate location in one of said channels, means formed on at least one of said removable glazed sash and on the said extra screened sash for mutual engagement for facilitating storage of the extra screened sash in elevated position in the said storm window assembly.
2. A storm window assembly comprising in combination a master frame, a pair of glazed sash removably positioned in the said master frame and an extra interchangeable screen sash for alternate location in the said master frame, means formed on the said glazed sash and on the said extra screened sash for interengagement for facilitating storage of the extra sash in elevated position in the said storm window assembly.
3. In a storm window assembly including a master frame having means for receiving a pair of removable glazed sash and an interchangeable extra screened sash, means formed on one of said glazed sash and the extra sash engageable with one another for facilitating storage of the extra sash in elevated position in the said storm window assembly.
4. In a storm window including a frame and a plurality of interchangeable sash, including at least two glazed sash and one screened sash, means for storing one of the said sash in the storm window, said means consisting of T-headed extensions formed on the top and bottom rails of certain of said sash and adapted to engage each other to retain at least one of the said sash in elevated relation to the others in the said frame.
